The ornamental design for a soap holder, as shown and described.

DESCRIPTION

FIG. 1 is a top perspective view of the soap holder showing my new design;

FIG. 2 is a bottom perspective view thereof;

FIG. 3 is a side elevation thereof;

FIG. 4 is a second side elevation thereof;

FIG. 5 is a top plan view thereof;

FIG. 6 is a bottom plan view thereof; and,

FIG. 7 is a cross-section view taken along line 7-7 of FIGS. 1 and 5.

The broken-lines of the figures depict a conical indentation in the base of the soap holder. The broken lines shown in the figures represent portions of the soap holder that form no part of the claimed design.
